(22) Filed: **Aug. 12, 2011**

CLAIM

(51) **LOC (9) Cl. 20-02**

The ornamental design for a male hygiene wiper holder appliance with upper storage and lower disposal units, as shown and described.

(52) **U.S. Cl. D6/519**

DESCRIPTION

(58) **Field of Classification Search** D6/515-524;

FIG. 1 is a top, front, and left side perspective view of a male hygiene wiper holder appliance with upper storage and lower disposal units showing my new design;

D34/1, 11; 211/13.1, 71.01, 85.19, 88.01;
221/33, 45, 282-286; 248/905; 312/34.1,
312/34.4

FIG. 2 is a front elevational view thereof;

See application file for complete search history.

FIG. 3 is a rear elevational view thereof;

FIG. 4 is a left side elevational view thereof;

FIG. 5 is a top plan view thereof; and,

FIG. 6 is a bottom plan view thereof.
